ENCLOSURE FOR ALTERNATING CURRENT APPARATUS

Edwin G. Gaynor, Fairfield, Conn.

Application February 13, 1942, Serial No. 430,762

6 Claims. (Cl. 175—361)

This invention relates to new and useful improvements in reactors or chokes.

The objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing—

Fig. 1 is a top plan view, with a part broken away, of the device of the invention;

Fig. 2 is a transverse sectional view taken as along the plane of the line 2—2 of Fig. 1;

Fig. 3 is a side elevational view of an embodiment of the invention; and

Fig. 4 is a plan view of a small portion of the enclosure of the invention on a greatly enlarged scale.

Referring in detail to the drawing my improved reactor comprises a sealed unit made up of a body 10 of E-shaped laminations, a keeper 11 also of laminated construction, a coil 12 about the intermediate leg of the body 10, and a box or casing 13 enclosing the laminated structures and the coil. Casing 13 comprises a hollow body 14 open at its upper side and a cover 15 also hollow and open at its underside. A pair of eyelets 16 in the top wall of the cover 15 define openings through which pass leads 17 soldered or otherwise connected with the coil 12.

Casing body 14 and cover 15 are made of a mixture or composition including asbestos. Body 14 and cover 15 may be made by blanking them from a sheet and then folding the blank and connecting the edges of the side walls in any suitable manner providing a seamed construction. However the body and cover shown are of drawn construction and therefore seamless. This is the preferred construction both by reason of the increased strength and by reason of the fact that the resulting container is solid or continuous with no seams or cracks of any kind.

In assembling the reactor of the invention the reactance unit comprising the laminated construction and the coil is assembled and secured together as by a U-shaped clamp 18 or the like. Then a plastic material, as pitch which melts at a high temperature as in the neighborhood of 375° F., is poured into the casing body 14. Thereafter while the pitch is molten the reactance unit is placed in the body 14 with the leads 17

reeved through the eyelets 16. Now the body 14 is filled with the pitch and the cover 15 is disposed over the upper side of the body and with its side walls 19 within the body after which the cover is pushed or forced into place with its side walls 19 within and in telescoping relation with the side walls 20 of the body but at the outer sides of the reactance unit. When cover 15 does not have a tight fit some of the pitch is forced up between the side walls of the cover and the side walls of the body.

When the pitch solidifies it secures the cover 15 to the body 14 and secures the reactance unit within the casing 13 and against any casual movement relative thereto. In the drawing the solid pitch is indicated by the reference character 21 and it is noted that the pitch completely fills the casing 13 about the reactance unit so that in effect a solid unit is made up and this unit is the complete reactor of the invention. Any suitable bracket or clamping structure may be used for mounting the improved reactor as, for example, a U-shaped clip or strap.

In the reactor described the improved casing 13 being drawn of a mixture including asbestos has many advantages. This casing deadens the hum incidental to any alternating current reactance. In this connection it is noted that the bottom wall 22 of the casing body 14 is bulged inwardly and that the reactance unit is disposed substantially centrally with respect to said wall. Thus when the device of the invention is disposed on a support as suggested as 23, the enclosure 13 rests on its edge portions 24 and the reactor unit is accordingly maintained spaced from the support whereby transmission of vibrations to the latter from the former is reduced or eliminated. Further the casing is fire proof and an electrical insulator. It has the property of insulating against outgoing heat generated in the coil 12 while the device is in use and the structure has peculiar properties in the matter of the dissipation of the heat generated within the unit.

With the present construction the casing insulates against outgoing heat in that the casing does not become excessively hot at one spot, that is in the immediate vicinity of the coil 12, but the heat generated at the coil is dissipated throughout the casing so there is no dangerous concentration of the heat at any one point. In addition the casing of the invention has a very large radiating surface so that the heat in addition to being dissipated throughout the casing is rapidly dissipated from the casing owing to the

presence of such large radiating surface. This large radiating area is due to the fact that the surface of the casing is rough and not smooth as in the case of metal reactor casings. The fact that the surface of casing 13 is rough as suggested in Fig. 4 provides for a greatly increased area of radiating surface so that the heat generated by the coil 12 during use of the improved reactor is rapidly dissipated.

Fig. 4 suggests the roughness of the surface of the casing 13 and in such figure the asbestos fibres in the mixture from which the casing is formed are suggested at 25 and it is noted that the surface of the casing is not smooth and slick but is rough and porous being made up of microscopic hills and valleys so that an extremely large surface area is available for the rapid dissipation of heat from the interior of the device.

Having thus set forth the nature of my invention, what I claim is:

1. An enclosure for alternating current apparatus comprising a rectangular box-like body open at its upper side and including integral outer side walls and a bottom completely closing the space between said walls, a hollow box-like cover open at its lower side and including integral outer side walls and a top completely closing the space between said walls, said outer walls of the cover adapted to telescope with those of said body with said top closing the open upper side of the body, and said body and cover each of an asbestos composition for insulation and the better distribution of heat throughout said enclosure and having rough fibrous exterior surfaces providing increased surface area for the rapid dissipation of heat generated by means within the body.

2. The enclosure as in claim 1 wherein said body has its bottom wall inwardly bowed from the lower edges of its side and end walls to support an apparatus within the body in upwardly spaced relation to the lower edges of the side and end walls of the body.

3. In an electrical device, an electrical unit, a casing enclosing said unit and comprising an integral box-like body open at its upper side and including a bottom and side walls, an integral hollow box-like cover open at its lower side and including a top and side walls of which the latter are disposed to telescope with those of said body with said top closing the open upper side of the body, said body and cover each of an asbestos composition for insulation and the better distribution of heat throughout said casing and having rough fibrous exterior surfaces providing increased surface area for the rapid dissipation of heat generated by said unit, and an integral mass of a set plastic material filling said body about said unit and adhering to said body and cover

and securing said cover in place closing said upper side of the body.

4. In an electrical device, an alternating current unit including a rectangular body and a coil extending above and below the upper and lower sides of said body, a rectangular casing completely about said unit and including a bottom wall adapted to be disposed toward a support, a top wall opposite said bottom wall, and outer side walls, said unit disposed with a portion of its coil toward said bottom wall, and said bottom wall bulged inwardly substantially from its edges whereby when the device is supported with said bottom wall disposed toward the support the device is supported from the edge portions only of said bottom wall with the coil of said unit spaced from such support to prevent the direct transmission of vibrations from the former to the latter.

10 5. In an electrical device, an alternating current unit including a rectangular body and a coil extending above and below the upper and lower sides of said body, a rectangular casing completely about said unit and including a bottom wall adapted to be disposed toward a support, a top wall opposite said bottom wall, and outer side walls, said unit disposed with a portion of its coil toward said bottom wall, said bottom wall bulged inwardly substantially from its edges whereby 15 30 when the device is supported with said bottom wall disposed toward the support the device is supported from the edge portions only of said bottom wall with the coil of said unit spaced from such support to prevent the direct transmission 35 of vibrations from the former to the latter, and said bottom wall of a non-metallic fibrous material whereby not to readily transmit such vibrations.

6. In an electrical device, an alternating current unit including a rectangular body and a coil extending above and below the upper and lower sides of said body, a rectangular casing completely about said unit and including a bottom wall adapted to be disposed toward a support, a top wall opposite said bottom wall, and outer side walls, said unit disposed with a portion of its coil toward said bottom wall, said bottom wall bulged inwardly substantially from its edges whereby when the device is supported with said bottom wall disposed toward a support the device is supported from the edge portions only of said bottom wall with the coil of said unit spaced from such support to prevent the direct transmission of vibrations from the former to the latter, and 50 55 an integral mass of a set plastic material filling said casing about said unit and adhering the casing and unit.

EDWIN G. GAYNOR.
